CLAIM

The ornamental design for a recreational floatation device for a plurality of users with cross-bar, as shown and described.

DESCRIPTION

FIG. 1 is a perspective view of a recreational floatation device for a plurality of users with cross-bar design; FIG. 2 is a top plan view thereof; FIG. 3 is a left side elevational view thereof, with the right side elevation being a mirror image; FIG. 4 is a front elevational view thereof; FIG. 5 is a rear elevational view thereof; and, FIG. 6 is a bottom plan view thereof.

FIG. 1

FIG. 2

FIG. 3

FIG. 4

FIG. 5

FIG. 6
